UNITED STATES PATENT OFFICE.

EBENEZER HILL, OF NORTH STAMFORD, CONNECTICUT, ASSIGNOR TO THE HILL COMPRESSOR & PUMP COMPANY, OF NEW YORK, N. Y., A CORPORATION OF DELAWARE.

ROTARY PUMPING MACHINE.

Application filed September 1, 1926. Serial No. 132,941.

This invention relates to a unitary direct connected motor driven rotary pumping machine, that is, a machine for pumping air and other gases which has the pump rotor 5 directly connected to and driven by the rotor of an electric motor.

The object of the invention is to so arrange, combine, construct and enclose the pumping and motor elements that a compact machine of this character will be produced which machine will start easily, thus enabling the use of a relatively small sized motor, and will run with high efficiency for a long period of time.

This object is attained by locating the pumping elements of a pump of the internal gear type on the base of an enclosing housing so that they will rotate in a horizontal plane, the base forming one wall of the pumping chamber, and mounting the motor in the housing directly above the pump with the motor rotor, that also turns in a horizontal plane, and the pump rotor fixed to the same vertical shaft. Arranged in this manner the pump rotor carries the motor rotor and the combined weights of the rotors during operation holds the pumping elements down to the base and prevents leakage of gas across them. When current is turned on to start the motor there is for a moment a slight movement of the motor rotor in an axial direction, and this is utilized to lessen the weight of the parts and relieve the friction of the pump elements 30 against the base, thus enabling the motor to start and obtain speed easily and quickly. Lubricant is placed in the housing which encloses both the pump and motor, and means are provided in the housing so that 40 while all of the parts will be automatically lubricated, the discharged gas will be freed of lubricant.

In the accompanying drawings Fig. 1 shows a vertical section of a gas pumping machine that embodies the invention. Fig. 2 shows a horizontal section of the same machine on the plane indicated by the dotted line 2-2 on Fig. 1. Fig. 3 is an enlarged vertical section of a portion of the lower 50 part of the machine on the plane indicated by the dotted line 3-3 on Fig. 2. Fig. 4 is a horizontal section on the plane indicated by the dotted line 4-4 on Fig. 1. Fig. 5 is a plan of the base of the machine with a small part broken away. Fig. 6 is a vertical

section of the machine with a modified arrangement for lubricating the parts and separating the lubricant from the discharged gas.

The base 1 of the machine illustrated is a 60 casting of circular outline, and the dome-shaped housing 2 is tightly secured to the base by a ring 3 fastened to the base by screw bolts 4. In the base is an intake chamber 5 for the entrance of the gas to be 65 pumped. This chamber is designed to be connected to the source of supply by passage 7 and pipe 8. An inwardly opening equalizing valve 9 is set in the base between the passage 7 and the chamber 5 to permit 70 the inflow of gas to, but prevent outflow of gas from this chamber. There is also in the base a chamber 10 into which the pump discharges the pumped gas. A discharge passage 11 in the base is designed to be connected by pipe 12 with the receiver for the pumped gas. 75

The pump illustrated is of the type shown and described in U. S. patent to Hill #1,486,835, granted March 11, 1924, which 80 pump has an internally toothed rotatable driving gear or annulus engaged by an externally toothed rotatable driven gear or pinion, the pinion being mounted within and eccentric to the annulus and having fewer 85 teeth than the annulus which teeth so contact that during rotation of the annulus and pinion, pockets or chambers open between them to receive gas and close to pump the gas therefrom. 90

A smoothly finished surface 13 is formed on the top of the base at the center and rotatable on this surface are the pinion 14 and the annulus 15. The pinion is retained in position by a stud 16 that extends upward 95 from and is fixed to the base. Anti-friction bearings 17 are interposed between the stud and pinion in order that the latter may rotate freely. The annulus, which in this machine is the pump rotor, is fastened by 100 screws 18 to a disk 19 that forms the head of the vertical shaft 20. The axis of the shaft which carries the annulus and the axis of the stud which retains the pinion are eccentric with relation to each other, as is necessary in this class of pumps. The lower end of the shaft is retained in position by a journal bearing 21 supported by a spider 22 that is secured to the base. At the upper end the shaft is journaled in a bearing 23 110

fastened to the top of the casing 24 that is secured to the shell 25 which is fixed to the base. It is preferred that the casing be closed while the shell has openings 26 near its lower edge to permit of free communication between the inside and outside of the shell. The shell may also have perforations 27 (Fig. 6) if desired.

The motor which is illustrated as used in this machine is of the commercial split-phase induction type, but any type of motor may be used. The core 28 of the motor rotor is fastened to the shaft between the bearings, and the rotor laminations 29 are fastened on this core as usual. The field laminations 30 are fastened to the inner wall of the casing 24 and the field coils 31 are wound on these laminations in the approved way. Mounted on the upper end of the motor rotor core and suitably insulated by the disk 32 are the circuit opening switch brushes 33 that contact with the stationary segments 34 on the insulating sleeve 35 when the rotor is idle, but which under centrifugal action after the rotor starts fly out, as is well known. Binding posts 36 are fastened to the base and connected on the outside to these posts are the service wires 37 (Fig. 1) and on the inside the motor leads 38 (Fig. 2).

Ports 39 (Figs. 3 and 5) are made from the intake chamber 5 up through the base to the surface 13 which forms one wall of the pumping chamber. These ports are located on the intake side, that is, the side on which the cavities between the teeth of the annulus and pinion open during rotation (Fig. 2). A port 40 (Fig. 5) opens from the surface 13 to the discharge chamber 10. This port is on the discharge side, or the side on which the cavities between the annulus and pinion teeth close (Fig. 2). By the rotation of the pumping parts gas is drawn in through the ports 39 from the chamber 5, and after being compressed is discharged through the port 40 to the chamber 10.

A pipe 41 is led from the discharge chamber to a cavity 42 above the upper end of the shaft so that the gas pumped is delivered from this pipe over the top of the shaft and whatever liquid lubricant the gas contains will drop and work down and lubricate the shaft.

The upper shaft bearing 23 has a petticoat 43 that extends downward into a cavity 44 in the top of the motor rotor core to prevent the lubricant from being thrown from the shaft onto the motor contacts. A passage 45 is made obliquely downward through the motor rotor core to allow surplus lubricant to drain into the lower part of the housing.

In the form of machine shown in Fig. 1, the pumped gas passes from above the top of the shaft through openings 46 into the housing and works its way upward around

the outer edges of the solid conical baffle plates 47 and through the openings 48 in the perforated baffle plates 49 to the space 50 in the upper part of the housing. These baffle plates collect lubricant from the gas allowing it to flow down and drop into the lower part of the housing. The baffle plates are supported by a tube 51 that opens at its upper end into the space in the housing above the baffle plates and that opens at its lower ends into a passage 52 formed in a plug 55 screwed into the top of casing 24. A pipe 53 leads from this passage 52 to the discharge passage 11 so that when the motor is running the pump will draw gas in through the intake pipe 8 and discharge the gas under pressure and free of lubricant through the discharge pipe 12.

In the form illustrated in Fig. 6 the baffle plates are omitted and the compressed gas is discharged from the pipe 41 directly into the upper part of the housing. Such liquid lubricant as the discharged gas carries is allowed to flow down around the shaft and be deposited in the bottom of the casing as before described. From the space in the housing the gas under pressure passes through the perforations 27 in the shell which supports the motor casing, and up around the motor parts to the pipe 54 which leads from the top of the casing over the motor, to the discharge passage 11. As the motor rotor turns very rapidly whatever lubricant is contained in the gas that passes through the passage 45 in the motor rotor core is thrown out and separated from the gas by centrifugal action.

With the machine construction as described when the motor circuit is closed the initial impulse which acts to thrust the motor rotor axially, is employed to tend to lift the parts and reduce the friction between the pump elements and the surface 13 which forms one wall of the pumping chamber. This reduces resistance to the motor torque so that the motor obtains its speed and power at once. As the armature after the first rush of current settles back the weight of the motor rotor, the shaft and the pump rotor holds the pump elements down to the wall 13 of the pump chamber so as to prevent leakage across the faces of the teeth of the annulus and pinion from one cavity to the other. For certain applications this obviates the necessity of providing thrust bearings for the motor and pump, and arranging spring means to hold the pumping elements in contact with the wall 13, and as the motor starts freely a motor of relatively small size may be employed. As the housing is tight the pump runs in a medium that is under the discharge pressure and consequently the liability of leakage between the pump parts is reduced to a minimum. Furthermore this permits the lower part of the

housing to hold liquid lubricant by means of which the wearing parts are automatically lubricated, and yet the gas which is finally discharged is freed of lubricant.

5 The invention claimed is:

1. A pumping machine comprising intermeshing toothed pumping elements eccentric with relation to each other and mounted to rotate in a horizontal plane, a shaft extending vertically upward from the pump rotor, and an electric motor mounted above the pumping elements with its rotor fixed to said shaft and adapted to rotate in a horizontal plane with its weight transmitted by 15 the shaft to the pump rotor.

2. A pumping machine comprising intermeshing toothed pumping elements eccentric with relation to each other and mounted to rotate in a horizontal plane, an electric motor 20 mounted above the pumping elements with its rotor adapted to rotate in a horizontal plane, and a vertically movable shaft connecting the pump rotor and motor rotor whereby the pump rotor and the motor rotor 25 will rotate and move axially together.

3. A pumping machine comprising intermeshing toothed pumping elements eccentric with relation to each other and mounted to rotate in a horizontal plane, an electric motor 30 mounted above the pumping elements with its rotor adapted to rotate in a horizontal plane, a vertical shaft connecting the pump rotor and motor rotor, and a housing enclosing the pump and adapted to hold lubricant, the pump discharge opening into said 35 housing whereby the pump may be operated in lubricant under discharge pressure.

4. A pumping machine comprising intermeshing toothed pumping elements eccentric with relation to each other and mounted to 40 rotate in a horizontal plane, an electric motor mounted above the pumping elements with its rotor adapted to rotate in a horizontal plane, a vertical shaft connecting the pump rotor and motor rotor, and a housing enclosing the pump and motor, with the discharge from the pump opening into said 45 housing, whereby the pump and motor are operated in a medium under discharge pressure.

5. A pumping machine comprising intermeshing toothed pumping elements eccentric with relation to each other and mounted to 50 rotate in a horizontal plane, an electric motor mounted above the pumping elements with its rotor adapted to rotate in a horizontal plane, a vertical shaft connecting the pump rotor and motor rotor, and a duct from the 55 pump discharge to the upper bearing of said shaft.

6. A pumping machine comprising intermeshing toothed pumping elements eccentric with relation to each other and mounted to 60 rotate in a horizontal plane, an electric motor mounted above the pumping elements with

its rotor adapted to rotate in a horizontal plane, a vertical shaft connecting the pump rotor and motor rotor, journal bearings for the shaft above and below the motor rotor, a duct from the pump discharge to the shaft 70 above the upper bearing, and passages through the motor rotor below said upper bearing, through which gas passes and oil is separated from it by centrifugal action.

7. A pumping machine comprising intermeshing toothed pumping elements eccentric with relation to each other and mounted to rotate in a horizontal plane, an electric motor mounted above the pumping elements with its rotor adapted to rotate in a horizontal plane, a vertical shaft connecting the pump rotor and motor rotor whereby the pumping elements support the motor 80 rotor by which they are rotated.

8. A pumping machine comprising intermeshing toothed pumping elements eccentric with relation to each other and mounted to rotate in a horizontal plane, an electric motor mounted above the pumping elements with its rotor adapted to rotate in a horizontal plane, a vertical shaft connecting the pump rotor and motor rotor, a housing enclosing the pump and motor, with the discharge from the pump opening into said 90 housing, and means in the housing for separating lubricant from the gas discharged by the pump.

9. A pumping machine comprising intermeshing toothed pumping elements eccentric with relation to each other and mounted to 100 rotate in a horizontal plane, an electric motor mounted above the pumping elements with its rotor adapted to rotate in a horizontal plane, a vertical shaft connecting the pump rotor and motor rotor, a housing 105 enclosing the pump, the pump discharge opening into said housing, a duct leading from the pump discharge to the upper part of the shaft, and means above the pump and motor for separating lubricant from the gas 110 issuing from said duct.

10. A pumping machine comprising a supporting base having a horizontal surface which forms one wall of the pumping chamber, intermeshing toothed pumping elements eccentric with relation to each other and mounted to rotate upon said wall, an electric motor mounted above the pumping elements with its rotor adapted to rotate in a horizontal plane, and a vertical shaft connecting the pump rotor and motor rotor whereby the pumping elements are rotated by the motor 120 rotor and are retained in sealing contact with the horizontal wall of the pumping chamber by the combined weights of these 125 elements.

11. A pumping machine comprising a supporting base having a horizontal surface which forms one wall of the pumping chamber, said base also having an intake

- chamber and a discharge chamber with ports therefrom through said horizontal wall of the pumping chamber, intermeshing pumping elements eccentric with relation to each other mounted to rotate upon said wall, an electric motor mounted above the pumping elements with its rotor adapted to rotate in a horizontal plane, a vertical shaft connecting the pump rotor and the motor rotor whereby the pumping elements are rotated by the motor rotor and are retained in sealing contact with the horizontal wall of the pumping chamber by the weight of these elements.
12. A pumping machine comprising a supporting base having a horizontal surface which forms one wall of the pumping chamber, said base also having an intake chamber and a discharge chamber with ports therefrom through said horizontal wall of the pumping chamber, a housing tightly fitted to said base and enclosing intermeshing toothed pumping elements eccentric with relation to each other mounted to rotate upon said wall, an electric motor mounted above the pumping elements with its rotor adapted to rotate in a horizontal plane, and a shaft connecting the pump rotor and the motor rotor.
13. A pumping machine comprising pumping elements, an electric motor mounted above the pumping elements, a vertical shaft connecting the pump rotor and motor rotor, journal bearings supporting said shaft and permitting a longitudinal movement thereof, whereby the pumping elements support and are driven by the motor rotor, and a housing enclosing the pump and motor.
14. A pumping machine comprising pumping elements, an electric motor mounted above the pumping elements, a vertical shaft connecting the pump rotor and motor rotor, and a housing enclosing the motor and pump with the pump discharge opening into said housing and both the pump and motor subject to and operating in the discharge pressure.
15. A pumping machine comprising intermeshing toothed pumping elements eccentric with relation to each other and mounted to rotate in a horizontal plane, an electric motor mounted above the pumping elements with its rotor adapted to rotate in a horizontal plane, a rotatory and axially movable shaft connecting the pump rotor and motor rotor, and a housing enclosing the pump and motor.
